CLAIM

The ornamental design for a capping tool for medical needles and sharps, as shown and described.

DESCRIPTION

FIG. 1 is an enlarged perspective view of a capping tool for medical needles and sharps showing my new design; FIG. 2 is a front elevational view thereof, the rear elevational view being identical thereto; FIG. 3 is a left side elevational view thereof; the right side elevational view being the same as the left side; FIG. 4 is a top plan view thereof; and, FIG. 5 is a bottom plan view thereof.

FIG. 1

FIG. 2

FIG. 3

FIG. 4

FIG. 5
